AARON SHATKIN, OF NEW YORK, N. Y.

METHOD OF MAKING ELLIPSOIDAL SHELLS AND TUBES

Application filed April 28, 1930. Serial No. 447,941.

The present invention relates to a method of making ellipsoidal shells and tubes from sheet metal, and more particularly to the type in which the shell or tube has but a single seam and is free from corrugations. Such shaped shells and tubes are desirable in the construction of sheet metal candle sticks, salt shakers, loving cups and similar class of articles, also for buttons, handles and other ellipsoidal-shaped and barrel-shaped articles, or in the construction of components of articles requiring such shapes.

To this and other ends, the invention consists in the novel method hereinafter described, illustrated and claimed.

In the accompanying drawings, forming a part of this application, similar characters of reference indicate corresponding parts in all the views.

20 Figs. 1, 2 and 3 show types of shells used in making ellipsoidal shells with a soldered seam.

Figs. 4, 5 and 6 show types of shells used in making ellipsoidal shells with a clinched seam.

Figs. 7, 8 and 9 show types of shells used in making ellipsoidal tubes with a soldered seam.

Figs. 10, 11 and 12 show types of shells used in making ellipsoidal tubes with a clinched seam.

Fig. 13 is a view showing the completed ellipsoidal shell.

Fig. 14 is a view showing the completed ellipsoidal tube.

Fig. 15 is a section on the line G—G, showing a soldered seam.

Fig. 16 is a section on the line G—G showing an inside clinched seam.

40 Fig. 17 is a section on the line G—G showing an outside clinched seam.

Fig. 18 is a section on the line G—G showing a section of a tube or shell possible to be constructed by the method herein described.

Fig. 19 is a view showing an ellipsoidal tube used in the construction of a salt shaker.

Fig. 20 is a view showing an ellipsoidal tube used in the construction of a candle stick.

Fig. 21 is a view showing an ellipsoidal shell used in the construction of a door knob.

Fig. 22 is a view showing an ellipsoidal shell used in the construction of a button.

As the first step in carrying out this invention, a flat disc or piece of sheet metal is formed or shaped into a blank shell of the types shown in Figs. 1 to 12 inclusive.

Shell 30 shown in Fig. 1, is a portion of a spherical shell equal or less than a semi-sphere, of the type when a sphere is cut by a plane.

Shell 41 shown in Fig. 2, is a portion of a spherical shell, less than a semi-sphere, of the type when shell 30 is cut by a plane along line OK which passes through a diameter DC on the periphery thereof.

Shell 45 shown in Fig. 3, is a portion of a spherical shell, less than a semi-sphere, of a type when shell 30 is cut symmetrically by two planes along lines AM and BM, whose line of intersection lies below a diameter DC of the periphery thereof.

Shell 32 shown in Fig. 7, is made from shell 30, by punching two semi-circular notches 50 and 51 diametrically opposite to one another, having their centres in the rim of the shell at points D and C.

Shell 43 shown in Fig. 8, is made from shell 41, by punching two semi-circular diametrically opposite notches 50 and 51 having their centres in the rim of the shell at points D and C.

Shell 47 shown in Fig. 9, is made from shell 45, by punching two semi-circular diametrically opposite notches 50 and 51, using as centres therefor the points on the shell intersected by the line of intersection of the planes passing through lines AM and BM.

Shell 36 shown in Fig. 4, has in addition to shell 30, a cylindrical extension 54, in which extension and in the full height thereof is punched two diametrically opposite notches 33 and 34.

Shell 42 shown in Fig. 5, has in addition to shell 41, two semi-cylindrical intersecting extensions 37 and 53, having punched at their lines of intersection, two diametrically opposite notches 33 and 34 which are the full height of such extensions.

Shell 46 shown in Fig. 6, has in addition to shell 45, two semi-cylindrical intersecting extensions 37 and 53, having punched at their lines of intersection, two diametrically opposite notches 33 and 34 which are the full height of such extensions.

Shell 38 shown in Fig. 10, is made from shell 36, by punching two diametric opposite notches each of which have a semi-circular portion 39 and 40, using as centres therefor the lowest points in notches 33 and 34 in said shell 36.

Shell 44 shown in Fig. 11, is made from shell 42, by punching two diametrically opposite notches each of which have a semi-circular portion 39 and 40, using as centres therefor the lowest points in notches 33 and 34 in said shell 42.

Shell 48 shown in Fig. 12, is made from shell 46, by punching two diametrically opposite notches each of which have a semi-circular portion 39 and 40, using as centres therefor the lowest points in notches 33 and 34 in said shell 46.

Consider the circular periphery of shell 30, to be intersected by perpendicular diameters AB and CD, forming arc DAC which is hereinafter referred to as seam line S, and arc DBC which is hereinafter referred to as seam line T.

As the second step or operation, bend and close shell 30, clam-like, by bringing point A in contact with point B. Seam line S thereby comes or is made to come in full contact with seam line T, and thus there is formed an ellipsoidal shell 23 shown in Fig. 13.

As the final step, the seam ST is seamed by soldering, welding or clinching. However, this closing of the seam may be dispensed with, when the material of which the shell is made, yields to the clam-like bending and closing, and stays put and firm in its final shape as in Fig. 13, and at the same time, a closed seam is not necessary, as would be the case if the shell 23 would be used in the construction of a covered button as shown in Fig. 22.

To form the tube 24 shown in Fig. 14, either cut the shell in Fig. 13 at the planes E—E and F—F, or else by the process above described, using initially the blank shell 32, and subject same to the clam-like bending operation by bringing seam line S into contact with seam line T, using the line connecting the centres of the notches as an axis, and when lines S and T are in contact, the semi-circular notches 50 and 51 would close to form holes 35. The seam ST is seamed if required, or else left open if possible.

When it is desired to secure the seam ST of shell 23 by either the inside clinched seam shown in Fig. 16, or by the outside clinched seam shown in Fig. 17, I prefer to use initially the blank shell 36 shown in Fig. 4. Bring seam line S in contact with seam line T,

using as an axis for the clam-like bending operation, the line formed by connecting the lowest points of the notches 33 and 34. When seam lines S and T will be in full contact, then the shell 36 will be fully closed and shell 23 will be formed by such process. The cylindrical extended portions 54 and 54' are used for making either seam shown in Figs. 16 or 17.

When it is desired to secure the seam ST of tube 24 by either of said clinched seams, I prefer to use initially the blank shell 38 shown in Fig. 10. Bring seam line S in contact with seam line T, using as an axis for the clam-like bending operation the same axis as used in forming shell 23 out of blank shell 36. When seam lines S and T will be in full contact, then the notches 39 and 40 will close to form circular holes 35, and tube 24 will be formed by such process. The cylindrical extended portions 54 and 54' are used for making either seam shown in Figs. 16 or 17.

All of the blank shells shown in Figs. 1 to 12 inclusive, when subjected to the clam-like bending and closing operation herein described, so that seam line S is brought in contact with seam line T, will form either ellipsoidal shell 23, or else ellipsoidal tubes 24, depending upon which are used. Blank shells shown in Figs. 1 to 6 inclusive, are used for making ellipsoidal shells 23. The remainder of the blank shells are used for making ellipsoidal tubes 24. Those shells having metal portions above the seam lines, are used preferably when the seam is to be of the clinched variety. Those shells having no metal portions above the seam lines, are used when the seam is to be soldered, or just left open, meaning, unseamed, but may also be used for a clinched seam.

When it is desired to form an ellipsoidal shell 23 which is tall and slender, use initially shells 41 and 42. If ellipsoidal tubes 24 of similar proportions are required, use blank shells 43 and 44.

When it is desired to form ellipsoidal shells 23 which are short and stout, use initially shells 45 and 46. For ellipsoidal tubes 24 of similar proportions, use blank shells 47 and 48.

In the construction of silverware articles, it is desirable to make shell 23 and tube 24 to have a cross-section similar to the section shown in Fig. 18. For such purpose, use a blank shell which instead of being a portion of a spherical shell, is a portion of an ellipsoidal shell as shell 53 shown in Fig. 1.

The uses to which the ellipsoidal shells 23 and the ellipsoidal tubes 24 can be put are numerous. A few adaptations are shown in the drawings. In Fig. 19, tube 24 serves as the salt compartment of a salt shaker having a perforated cap 25, and a base 26. In Fig. 20, tube 24 is used in the construction of a candle stick by having base 28 soldered into one end

thereof, and candle socket 27 being soldered into the other end. In Fig. 21, shell 23 is soldered to a hub 29, and thus serves in the construction of a door knob. In Fig. 22, shell 23 is soldered to a little hub 31 which has drilled in it a hole 52, and thus serves in the construction of a button, which may be covered with either cloth or leather 49. The shell 23 and the tube 24 may be cut in half at plane G—G and used in the construction of cups of a shape which would be very difficult to either spin or stamp.

From the foregoing it will be seen, that there has been provided an improved method of forming ellipsoidal shells and ellipsoidal or barrel-shaped tubes from sheet metal, so that the shell or tube has but one seam and is free from corrugations.

I claim:—

1. The method of forming shells which consists in shaping a flat sheet into an open curvilinear shell having all points on its rim lying in a single plane, and bending said shell clam-like until closed.

2. The method of forming shells which consists in shaping a flat sheet into an open curvilinear shell having all points on its rim lying in a single plane, bending said shell clam-like until the meeting edges are in full contact, and then seaming the meeting edges.

3. The method of forming ellipsoidal shells which consists in shaping a flat sheet into a portion of a spherical shell, and bending said shell clam-like until the meeting edges are in full contact.

4. The method of forming ellipsoidal shells which consists in shaping a flat sheet into a portion of a spherical shell, bending said shell clam-like until the meeting edges are in full contact, and seaming the meeting edges.

5. The method of forming tubes which consists in shaping a flat sheet into an open curvilinear shell, punching two semi-circular diametrically opposite notches in the shell, having their centres in the rim of the shell, and bending the shell clam-like until the notches close to form circular holes and the meeting edges are in full contact.

6. The method of forming tubes which consists in shaping a flat sheet into an open curvilinear shell, punching two semi-circular diametrically opposite notches in the shell, having their centres in the rim of the shell, bending the shell clam-like until the notches close to form circular holes and the meeting edges are in full contact, and seaming the meeting edges.

7. The method of forming ellipsoidal tubes which consists in shaping a flat sheet into a portion of a spherical shell, punching two semi-circular diametrically opposite notches in the shell having their centres in the rim of the shell, and bending the shell

clam-like about the line connecting the centres of the notches as an axis, until the notches close to form circular holes and the meeting edges of the shell are in full contact.

8. The method of forming ellipsoidal tubes which consists in shaping a flat sheet into a portion of a spherical shell, punching two semi-circular diametrically opposite notches in the shell having their centres in the rim of the shell, bending the shell clam-like about the line connecting the centres of the notches as an axis, until the notches close to form circular holes and the meeting edges of the shell are in full contact, and seaming the meeting edges.

In witness whereof, I affix my signature.

AARON SHATKIN.
